US00D751575S

(12) **United States Design Patent**
Kim et al.

(10) **Patent No.:** **US D751,575 S**
(45) **Date of Patent:** **** Mar. 15, 2016**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **So-Ra Kim**, Seoul (KR); **Dong-Hoon Sohn**, Seoul (KR); **Seo-Young Yoon**, Seoul (KR); **Joo-Hyung Lee**, Seoul (KR); **You-Jin Im**, Seoul (KR)

(73) Assignee: **Samsung Electronics Co., Ltd.,**
Suwon-si (KR)

(**) Term: **14 Years**

(21) Appl. No.: **29/487,867**

(22) Filed: **Apr. 14, 2014**

(30) **Foreign Application Priority Data**

Feb. 21, 2014 (KR) 30-2014-0008989

(51) **LOC (10) Cl.** **14-04**

(52) **U.S. Cl.**

USPC **D14/485**

CLAIM

We claim the ornamental design for a display screen or portion thereof with graphical user interface, as shown and described.

DESCRIPTION

The sole FIGURE is a front view of a display screen or portion thereof with graphical user interface showing our new design. The broken line showing of the display screen or portion thereof with graphical user interface is for the purpose of illustrating environmental structure and forms no part of the claimed design.

1 Claim, 1 Drawing Sheet
